UNITED STATES PATENT OFFICE.

LEWIS MASON LEE, OF FRANKFORT, KENTUCKY

CULTIVATING APPARATUS.

Application filed March 18, 1924. Serial No. 700,111.

This invention relates to improvements in cultivating instruments, and more particularly to such as are susceptible of use from the time of planting to maturity.

5. An object in view is the production of a light, durable construction adapted for use singly or in multiple, and so designed as to utilize a variable number of plates or shovels.

10 A further object is the flexible retention of the plate frame at various angles to the line of draft.

With these and further objects in view as will in part hereinafter become apparent and in part be stated, the invention comprises certain novel constructions, combinations and arrangements of parts as subsequently specified and claimed.

In the accompanying drawings,

20 Figure 1 is a view in side elevation of a plow or cultivator embodying the features of the present invention.

Figure 2 is an end view thereof.

Figure 3 is a plan view thereof.

25 Figure 4 is a side elevation of the inside of one of the frame plates detached and seen on an enlarged scale, the clamping bolts being seen in transverse section and the pivot pin in side elevation.

30 Figure 5 is a vertical section through the complete frame, parts being broken away and the section being taken on a plane equal to that indicated by line 5—5 of Figure 4.

Referring to the drawings by numerals, 1 indicates a draft beam formed of a strap, preferably of steel or other appropriate material, bent and folded back upon itself so as to produce a curved or parti-circular portion 2 at the rear from which extend forwardly the two converging arms or laps of the strap, receiving between their forward portions the block 3 to which the clevis-receiving loop 4 is attached. Obviously, any type of draft connection desired may be caused to engage loop 4. Block 3 is bolted or riveted or otherwise appropriately and effectively anchored to the draft beam 1, between the arms thereof.

Within the curved portion 2 of beam 1 is arranged a plate 5, which is welded or otherwise appropriately anchored to the beam 1. Extending upwardly through plate 5 is a pivot pin 6 having an aperture just above the plane of the upper face of the plate 5 through which aperture extends a locking key 7. The lower end of pin 6 is formed into

a ball 8. Arranged transversely of and just beneath draft beam 1 is a plate frame made up of bars 9, 9, secured together by clamping bolts 10, 10. Each bar 9 is formed with a parti-globular recess 11 registering with each other and jointly forming a socket for ball 8. Each of the bars 9 is formed with a groove leading upwardly from the respective recess 11 for accommodating the body of pin 6, so that, while the pin is effectively anchored between bars 9, the frame made up of said bars is free to swing angularly about the pin and thus assume various angular relations to the line of draft. The parts are preferably proportioned to cause the upper edge of the plate frame, that is the frame made up of bars 9, to rest against the under face of plate 5.

A groove 12, similar to that extending upwardly from recess 11 in each plate 9, extends downwardly therefrom to receive a standard of a plate or cultivator shovel. Similar grooves 13, 13, similarly registering are formed at various places in the length of bars 9. Grooves 13, however, preferably extend entirely across the full width of the respective bar, there being preferably a number of equally spaced grooves 13 for providing an odd number of shovel standards. When grooves 12 are counted, the grooves 13 nearest to grooves 12 being spaced the same distance from grooves 12 as the nearest grooves 13 are spaced from each other, whereby, when all of grooves 13 and 12 are employed, there will be an odd number of shovel standards spaced equally throughout the length of the plate frame.

Five such standards have been provided for in the odd number shown in the drawings, but, obviously, the number may be varied as desired. However, when from the spacing of rows, or angularity of frame, or other cause, it becomes desirable to employ an even number of shovel standards, the grooves 12 are not utilized, and the grooves 13 nearer grooves 12 at each side are also not employed, but instead there are provided extra grooves 14, 14, spaced apart the same distance that each is spaced from the nearer end grooves 13, whereby, by the use only of the end grooves 13 and the grooves 14, an equal number of shovel standards may be used and spaced equally.

One of plates 9, preferably the rear one, is provided with a set screw 15 for each pair of grooves 12, 13 and 14, and the standards

16, 18 extending into the grooves are clamped by the set screws for locking the standards in a given position. The lower end of each standard 16 carries a plate or shovel 17, and set screws 15 serve to cause the shovels to face forwardly, when properly set, regardless of the angle of the shovel frame to the line of draft.

Fixed to each end of the shovel frame is a 10 forwardly-extending eye 18 to which is connected a coiled spring 19. Springs 19 extend forwardly on an incline and have their forward ends anchored, preferably adjustably, to the draft beam 1, so that the shovel frame 15 may swing on the pivot pin 6 whenever a shovel 17 strikes an obstacle requiring flexing of the parts. The anchorage of each spring 19 to beam 1 is susceptible of wide variation within the spirit and intent of this 20 invention, and one preferred form is shown as consisting of a block 20 having an eye 21 engaging the respective spring. A bolt 22 engages each block 20 and extends through any of apertures 23, 23 formed in beam 1. 25 When the shovel frame is to extend normally at right angles to the line of draft, as seen in the drawings, the bolts 22 extend through transversely alined apertures 23, as shown, but, if it becomes desirable to vary the angle 30 of the shovel frame to the line of draft, one of the bolts 22 is placed in one of the forward apertures 23, while the other bolt 22 is placed in an aperture 23 as much in the rear as the other is forward. Thus the shovel frame 35 will be resiliently retained at any angle desired.

An appropriate handle or handles 24 is or are anchored to the beam 1 and located to be accessible to the operator. The cultivating apparatus is readily adapted for use singly or in gangs as desired.

What is claimed is:—

1. In cultivating apparatus, the combination of a draft beam, a shovel frame pivoted thereto, and springs anchored to the end portions of the frame and connecting the frame to the beam, the springs being adjustable along the beam for varying the points of purchase and the tension of the springs simultaneously.
2. In cultivating apparatus, the combination of a strap bent to form a curved portion and return arms providing a draft beam, a plate anchored in and conforming to the contour of the curved portion, and a shovel frame pivoted to the plate.
3. In cultivating apparatus, the combination of a draft beam, a pair of bars forming a shovel frame, and a pivot pin extending from the beam between the bars for connecting the frame pivotally to the beam, the bars being formed with registering grooves for receiving shovel standards, one pair of said grooves being in line with the pin.

60 4. In cultivating apparatus, the combination of a draft beam, a pair of bars forming a shovel frame, and a pivot pin extending from the beam between the bars for connecting the frame pivotally to the beam, the bars being formed with registering grooves for receiving shovel standards, one pair of said grooves being in line with the pin.

65 4. In cultivating apparatus, the combination of a draft beam, a pair of bars forming a shovel frame, and a pivot pin extending from the beam between the bars for connecting the frame pivotally to the beam, the bars being formed with registering grooves for receiving shovel standards, one pair of said grooves being in line with the pin, the bars being similarly grooved to accommodate the pin and the grooves for the pin terminating in parti-globular recesses, 70 and the pin being formed with a ball fitted within said recesses.

75 5. In cultivating apparatus, the combination of a draft beam, a pair of bars forming a shovel frame, and a pivot pin extending from the beam between the bars for connecting the frame pivotally to the beam, the bars being formed with registering grooves for receiving shovel standards, one pair of said grooves being in line with the pin, the several pairs of grooves being equally spaced apart, and the bars being formed with other similar grooves equally spaced with respect to themselves and some of the first-mentioned grooves and unequally spaced from 80 the other of the first-mentioned grooves.

85 6. In cultivating apparatus, the combination of a bent strap having return arms forming a draft beam, the strap having a curved portion at the bend, a plate fitted and anchored in said bent portion, a cultivator frame arranged transversely of the beam, a pin pivoted in the frame and extending through the plate, and a locking pin extending through the pivot pin at the opposite 90 side of the plate from the frame.

95 7. In cultivating apparatus, the combination of a bent strap having return arms forming a draft beam, the strap having a curved portion at the bend, a plate fitting and anchored in said bent portion, a cultivator frame arranged transversely of the beam, and a pivot pin extending from the frame into pivotal engagement with the plate.

100 In testimony whereof I affix my signature.

LEWIS MASON LEE.
